UNITED STATES PATENT OFFICE

JAMES KARAGEORGE, OF CHICAGO, ILLINOIS

DESIGN FOR A FAN

Application filed November 10, 1930. Serial No. 37,616. Term of patent 14 years.

To all whom it may concern:

Be it known that I, JAMES KARAGEORGE, a citizen of the United States, residing in Chicago, in the county of Cook and State of Illinois, have invented a new, original, and ornamental Design for a Fan, of which the following is a specification, reference being had to the accompanying drawing, forming part thereof.

In the drawings:—

I claim:—

The ornamental design for a fan as shown.

In testimony whereof I claim the foregoing as my invention, I affix my signature this 6th day of November, 1930.

JAMES KARAGEORGE.
